Primary Examiner — Anhdao Doan*(74) Attorney, Agent, or Firm* — Sughrue Mion, PLLC**CLAIM**

The ornamental design for mist generator for beauty treatment, as shown and described.

DESCRIPTION

FIG. 1 is a perspective view of mist generator for beauty treatment showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing a state that a bottle is detached thereof; and,

FIG. 9 is a front view of usage thereof;

The broken lines immediately adjacent the shaded areas represent the bounds of the claim, while all other broken lines are directed to environment and are for illustrative purposes only; the broken lines form no part of the claimed design.

The parallel wavy lines mean omission length and non-claimed portion which form no part of the claimed design.
